LATHER CHURN

George C. Mumford, Larchmont, N. Y.

Application August 29, 1949, Serial No. 112,948

7 Claims. (Cl. 259—99)

1.

This invention relates to lather churning and has particular relation to an improved lather churn which is specially adapted to form a heavy lather by finger manipulation of the user.

The lather churn of the present invention generally comprises a cup-shaped container containing a sponge, the sponge being provided with a vertically positioned finger hole adapted to receive a finger of the user whereby finger manipulation in the finger hole results in the formation of lather when a saponifiable compound is in the container and in its preferred form includes a perforated resilient sleeve lining the finger hole to protect the sponge from mutilation by continued finger manipulation. In another form, the invention generally comprises a cup-shaped container having an inturned rim to retard withdrawal of the sponge, the rim having an outwardly and upwardly extending flange to provide storage space for the lather created and to prevent overflow thereof.

An object of the invention is to provide a lather churn which is adapted to mix water and air with a saponifiable compound such as shaving cream, shaving powder, liquid soap, or solid soap by finger manipulation of the user so as to create a foamy lather.

Another object of the invention is to provide a lather churn which will accomplish the aforementioned object and which will be of relatively small, simple, durable and inexpensive construction.

Still another object of the invention is to provide a lather churn which will accomplish the foregoing objects and which will provide a storage space for retaining the lather formed in the device readily available for use.

Another object of the invention is to provide a lather churn which may be readily disassembled for cleaning or sterilizing purposes.

These and other objects of the invention will be better understood by reference to the following description and accompanying drawing in which:

Fig. 1 is a perspective view of a preferred form of the invention;

Fig. 2 is a sectional view taken on the line 2—2 of Fig. 1; and

Fig. 3 is a partially exploded view of the form of the invention shown in Fig. 1 with the elements partially broken away in section.

Referring now to the drawings, the lather churn in the present invention includes a cup-shaped container 10 having an inturned rim 11 in which a generally doughnut-shaped sponge 20 is positioned. It will be apparent that the inturned rim

2.

11 serves to retain the sponge within the cup-shaped retainer 10 during normal use although the sponge 20 may be withdrawn from the container 10 by compressing the sponge. The rim 11 of the container 10 is preferably provided with an upwardly and outwardly extending flange 12 which is shown in the form of a bell-shaped mouth opening. Although the container 10 with flange 12 may be unitary, in practice it has been found advantageous to join the rim 11 of the container 10 and the flange 12 at their adjacent edges by means of a collar 13 which is maintained on the inturned edge of the rim and provided with a peripheral groove 14, said groove being engageable with the adjacent edges of the rim 11 and flange 12 for securing them together. In this form of the invention the flange further serves to maintain the sponge 20 in position in the container 10.

20 In the preferred form, the container 10 and flange 12 are preferably formed of a resilient pliable material such as rubber. Preferably the collar 13 is formed of a non-resilient molded plastic although it will be understood that a resilient plastic material or a resilient rubber may be used to form the collar.

25 The lather-forming element generally comprises a doughnut-shaped sponge 20, as of rubber, having a vertically positioned finger hole 21. In a preferred form the finger hole 21 is lined with a resilient sleeve 22 having a number of perforations 23 to permit communication of the soap, water and air between sponge 20 and the finger hole 21. The sleeve 22 is preferably provided at its lower edge with an outwardly extending flange 24 to prevent withdrawal of the sleeve during normal use. As shown in the drawing, the upper edge of the resilient sleeve 22 may be provided with an outwardly extending flange 25 whereby the flanges 24 and 25 engage the sponge 20 to prevent relative movement therebetween and to prevent withdrawal of the resilient sleeve 22 during normal use of the device. The resilient sleeve 22 is preferably formed of soft pliable rubber.

30 35 40 45 The sleeve element also may be formed integrally by hardening the surface of the finger hole 21, as by vulcanization.

50 In operation, the cup-shaped container 10 may be conveniently held in one hand of the user with the bell-shaped flange 12 at the top. A small amount of water is placed in the cup to saturate the sponge and a suitable quantity of saponifiable compound is placed in the finger hole 21. The saponifiable compound may be in the form of a pellet adapted to fit into the bottom part of the

finger hole. The forefinger of the other hand of the user is inserted in the finger hole 21 and rotated to blend the saponifiable compound, water and air into a foamy lather. On continued manipulation, the lather will tend to rise upwardly out of the cup 10 and will lie exposed for use in the bell-shaped flange area 12. It will be apparent that the inturned rim 11 and the cup 10 will maintain the sponge 20 in the cup during use. It will also be apparent that the sleeve 22 will be retained in the finger hole 21 during manipulation by virtue of the lower flange 24 and that this retarding effect may be increased by providing an upper flange 25 and that the sponge 20 will be engaged therebetween. If desired the resilient sleeve 22 may be glued in the finger hole 21 to prevent rotary movement thereof relative to the sponge during manipulation.

It is desired to point out that one of the essential features of the present invention comprises the provision of a finger hole 21 in the sponge lather-forming element 20. It is also desired to point out that another important feature of the present invention is the provision of the upwardly and outwardly extending flange 12 to provide a storage space for the lather as it is created by finger manipulation. Still another important feature is the provision of the resilient perforated sleeve 22 lining the finger hole 21 so as to prevent mutilation of the sponge element 20 by continued finger manipulation.

It will be apparent that the present invention is subject to other modifications than those shown in the preferred embodiments illustrated in the drawing and described in the specification and it is intended that all such modifications within the realm of those skilled in the art come within the purview of the present invention as defined by the following claims.

I claim as my invention:

1. A lather churn comprising a cup-shaped container and a sponge in said container, said sponge being provided with a vertically positioned finger hole adapted to receive a finger of the user whereby finger manipulation in the finger hole results in the formation of lather when a saponifiable compound is in the container.

2. The lather churn set forth in claim 1 including a perforated resilient sleeve lining said finger hole to protect said sponge from mutilation by the finger of the user.

3. The lather churn set forth in claim 1 including a perforated resilient sleeve lining said finger

hole to protect said sponge, said sleeve having an outwardly extending flange on the bottom edge thereof engaging said sponge to prevent withdrawal of the sleeve from the borehole by the finger of the user.

4. The lather churn set forth in claim 1 including a perforated resilient sleeve lining said finger hole to protect said sponge, said sleeve having an outwardly extending flange at each end thereof engaging said sponge to prevent movement thereof relative to said sponge.

5. A lather churn comprising a cup-shaped container having an inturned rim to retard withdrawal of its contents, said rim having an outwardly and upwardly extending flange to provide storage space for the lather created and to prevent overflow thereof, and a sponge in said container, said sponge being provided with a vertically positioned finger hole adapted to receive a finger of the user whereby finger manipulation in the finger hole results in the formation of lather when a saponifiable compound is in the container.

6. A lather churn comprising a cup-shaped container having an inturned rim to retard withdrawal of its contents, a collar mounted internally on said rim, an outwardly and upwardly extending flange mounted on said collar to provide storage space for the lather created and to prevent overflow thereof, and a sponge in said container, said sponge being provided with a vertically positioned finger hole adapted to receive a finger of the user whereby finger manipulation in the finger hole results in the formation of lather when a saponifiable compound is in the container.

7. A lather churn comprising a cup-shaped container having an inturned rim to retard withdrawal of its contents, an outwardly and upwardly extending flange to provide storage space for the lather created and to prevent overflow thereof, said rim and said flange being joined by a peripherally grooved collar engageable with adjacent edges of said rim and said flange for securing them together and a sponge in said container, said sponge being provided with a vertically positioned finger hole adapted to receive a finger of the user whereby finger manipulation in the finger hole results in the formation of lather when a saponifiable compound is in the container.
